UNITED STATES PATENT OFFICE.

WILLIAM A. LEMON AND WILLIAM H. OTTO, OF CINCINNATI, OHIO.

SHAVING-CUP.

SPECIFICATION forming part of Letters Patent No. 716,067, dated December 16, 1902.

Application filed May 3, 1902. Serial No. 105,819. (No model.)

To all whom it may concern:

Be it known that we, WILLIAM A. LEMON and WILLIAM H. OTTO, citizens of the United States, residing at Cincinnati, in the county of Hamilton and State of Ohio, have invented new and useful Improvements in Shaving-Mugs, of which the following is a specification.

This invention relates to shaving-mugs; and the purpose of the present improvement is to provide a device of this class which is absolutely sanitary, inasmuch as it can be thoroughly flushed after each usage and fully remove any sediment or slime that may accumulate under the cake of soap which is held suspended and movably supported.

The invention consists in the construction and arrangement of the several parts, which will be more fully hereinafter described and claimed.

In the drawings, Figure 1 is a perspective view of a shaving-mug embodying the features of the invention. Fig. 2 is a transverse vertical section of the same. Fig. 3 is a horizontal section taken in the plane of the line 3 3, Fig. 2. Fig. 4 is a detail perspective view of a modified form of soap holder or support.

Similar numerals of reference are employed to indicate corresponding parts in the several views.

The numeral 1 designates a hollow cup-body preferably cylindrical in form and open at both ends. The lower end of the said body is loosely disposed in and freely removable from a lower tray 2, having a surrounding up-standing flange 3 and provided with radial ribs 4, on which the bottom of the body rests. The body 1 has an intermediate grip or handle 5 and a central circumferential outstruck bead 6 to form an inner concave seat 7. A soap-holding rod or support 8, with opposite reduced terminals 9, is disposed within the body 1 and has the said terminals loosely engaging the seat 7, this soap-holding rod or support being freely applicable to and removable from the seat through the medium of the inclined outstruck short bead 10, which is vertically disposed. A cake 11 of soap is mounted on the rod 8 and suspended within the body 1, as clearly shown by Figs. 2 and 3, the said soap being freely movable in view of the loose application of the rod or support

therefor to permit different portions of the same to be brought under the brush in forming lather, and thereby economize in the use of the soap as well as reduce the same regularly.

A modified form of the soap-holding rod or support is shown by Fig. 4 and comprises a rod 12, having opposite reduced terminals 13 and intermediate radial projections 14, around which the soap is adapted to be molded and be thereby held against movement on the rod.

It is preferred to form the parts of the device of suitable sheet metal and plate the same or in finer grades to construct the body 1, tray 2, and the soap-holding rod of silver. It is obvious that any suitable material may be used, and it is preferred that the opposite open ends of the body be surrounded by a bead or like blunt formation to overcome the presence of sharp edges.

In the use of the improved mug or cup the brush is inserted in the upper open end and vibrated over the soap to form a lather, as in the ordinary methods, and the drippings from the soap will fall into the tray below and in the spaces between the ribs 4. When it is desired to clean the mug or cup, the body 1 may be removed from the tray and freely flushed by permitting water to run therethrough to clean the same and dissolve all sediment or accumulation therein. The tray also may be readily cleaned, and thus the improved device as an entirety may be kept in an absolute sanitary condition.

The preferred form of the improved cup or mug has been shown and described; but it is obvious that changes in the form, size, proportions, and minor details may be resorted to without departing from the principle of the invention.

Having thus fully described the invention, what is claimed as new is—

1. A shaving-mug comprising a hollow body open at both ends and having soap-suspending means therein, and a tray in which the said body is removably disposed.
2. A shaving-mug comprising a hollow body open at both ends and having soap-suspending means therein, and a tray having ribs on which the body rests.
3. A shaving-mug comprising a hollow body open at both ends, a soap-holding means

movably and detachably held within the body, and a tray on which one end of the body rests.

4. A shaving-mug comprising a hollow body open at both ends formed with a circumferential bead at an intermediate point, a soap-holding device having the opposite terminals thereof removably and movably engaging the said bead, and a tray in which the said body rests.

5. A shaving-mug comprising a hollow body open at opposite ends, formed with a circum-

ferential bead, and a shorter bead intersecting the former bead, a soap-holding rod movably and detachably engaging the said bead, and a lower support for the body. 15

In testimony whereof we affix our signatures in presence of two witnesses.

WILLIAM A. LEMON.
WILLIAM H. OTTO.
